UNITED STATES PATENT OFFICE.

RICHARD VON HORVÁTH, OF VIENNA, AUSTRIA-HUNGARY, ASSIGNOR TO FELIX KUSCHENITZ, OF VIENNA, AUSTRIA-HUNGARY.

LIGHT-STRIKER.

971,380.

Specification of Letters Patent. Patented Sept. 27, 1910.

Application filed July 11, 1908. Serial No. 443,652.

To all whom it may concern:

Be it known that I, RICHARD VON HORVÁTH, a subject of the Emperor of Austria-Hungary, residing at No. 17 Landstrasser 5 gürtel, in Vienna, in the Empire of Austria-Hungary, have invented certain new and useful Improvements in Light-Strikers, of which the following is a specification.

Notwithstanding the development of the 10 match industry there is still a demand for light-strikers which will not fail in the open air, in a storm for example, and able to compete successfully with matches as regards cost, which is of great importance from an 15 industrial point of view. Light strikers in which powder caps are caused to explode by means of a percussion hammer so as to cause a slow match or tinder arranged in proximity to the place of explosion to glow, pre- 20 sent the defect that the explosion is frequently not produced, especially in damp weather, while even when the explosion does occur it does not always result in the kindling of the tinder. This renders these light- 25 strikers uncertain in operation and thus prevents their commercial success. The flints which are still sometimes used for striking a light demand special skill in using them for this purpose so that they do not come up to 30 present day requirements.

Now for some time substances or bodies have been known which emit sparks copiously and with a very slight amount of friction. These bodies, such for example as py- 35 rophoric metals or alloys, afford a means for obtaining a convenient industrial light striker which is always certain in its operation, and such a device forms the object of the present invention. As these bodies be- 40 come operative when but slightly heated, a sharp knife-like instrument is sufficient for producing the sparks for igniting a slow match. It is therefore only necessary to provide such a sharp piece of iron or steel 45 with a sleeve serving for the reception of the slow match the end of which is situated in close proximity to the edge of the piece of iron or steel. If therefore, with the end of the slow match protruding, this edge is 50 drawn quickly over the frictional surface

of the spark-emitting body, the slow match will invariably be kindled.

A form of light-striker in accordance with the present invention is illustrated by way of example in the accompanying drawing, 55 in which:—

Figure 1 shows it in longitudinal sections ready for use. Fig. 2 is a view showing the device ready for packing-up. Fig. 3 is a cross-section on the line III—III of Fig. 2, 60 and Fig. 4 shows the device in the packed or closed condition ready for the pocket.

a designates a steel sleeve somewhat sharpened at *b*. Another sleeve *c* is rigidly connected with this steel sleeve *a* and in them the slow match or tinder *d* is placed. The front end of the slow match is caused to protrude as far as the edge *b* of the steel sleeve *a*, when it is desired to strike a light. The frictional surface *f* of the spark-emitting body *e*, which may be of any suitable form, is preferably arranged at the front end of a protecting sleeve or socket *g* which is open at its other extremity. If the edge of the steel sleeve *a* is drawn rapidly over the frictional surface *f* in the direction indicated by the arrow *a'*, the sparks emitted ignite the end of the slow match *d*. When it is desired to extinguish the slow match it is only necessary to slide the steel sleeve *a* together with the sleeve *c* rigidly connected therewith into the protecting socket *g* (Fig. 4). The slow match or tinder may of course, be replaced by an inflammable sponge or the like. 75 80 85

What I claim and desire to secure by Letters Patent of the United States is:—

1. A light striker comprising a sleeve having a sharpened projection at one end, a slow match frictionally and adjustably contained within said sleeve, a second sleeve carrying on its outside a spark emitting body having a frictional surface for an independent cooperation with the sharpened projection of the first named sleeve, the second sleeve being closed at one end and open at the other end to receive the first sleeve with the projection and the ignited end of the slow match. 90 95

2. A light striker comprising a sleeve hav- 100

ing a sharpened projection at one end, a
wick frictionally and adjustably contained
within said sleeve, and a second sleeve hav-
ing on its outside a spark emitting body
5 having a frictional surface for an independ-
ent coöperation with said sharpened pro-
jection.

In testimony whereof I affix my signature
in presence of two witnesses.

RICHARD VON HORVÁTH.
